(57) **CLAIM**

The ornamental design for a scooter stand, as shown and described.

DESCRIPTION

FIG. 1 is a front perspective view of the scooter stand of the present invention showing our new design with the phantom lines depicting solely environmental structure and forming no part of the claim design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof;

FIG. 7 is a right side elevational view thereof; and,

FIG. 8 is a left side elevational view depicting the scooter stand in a collapsed stowed configuration.
